UNITED STATES PATENT OFFICE.

JAMES BARRY, OF HERCULES, CALIFORNIA, ASSIGNOR OF ONE-HALF TO DANIEL J. COTTER, OF HARRIS, KANSAS.

SNOW-MELTER.

1,333,373.

Specification of Letters Patent. Patented Mar. 9, 1920.

Application filed October 17, 1918. Serial No. 258,561.

To all whom it may concern:

Be it known that I, JAMES BARRY, a citizen of the United States, residing at Hercules, in the county of Contra Costa and 5 State of California, have invented new and useful Improvements in Snow-Melters, of which the following is a specification.

This invention relates to a device for cleaning snow from railway right-of-ways.

10 It is the principal object of this invention to provide simple and economical means for clearing snow from railway tracks without the use of power shovels and other expensively operated power mechanisms. The 15 present invention contemplates the use of a portable heating apparatus adapted to be carried upon a railway car or other suitable vehicle, and which will develop sufficient heat which may be applied to a snow drift 20 in a manner to melt the snow and thus move it from its obstructing position. The invention also contemplates the provision of means for mechanically breaking up the snow drift as it is melting. The invention 25 is illustrated in the accompanying drawing in which the figure discloses a diagrammatical view in side elevation of the entire apparatus.

Referring more particularly to the drawings, 10 indicates the bed of the flat car which is here shown as provided with trucks 11 and 12. Mounted upon one end of this bed or platform is a steam boiler 13 which may be supplied with fuel from any desired 35 source. In the present instance, however, a fuel oil tank 14 is mounted upon the platform and supplies the fuel to oil burners beneath the boiler by means of a supply pipe 15. The water tank 16 is also mounted upon 40 the platform and provides the necessary supply of water for the boiler. In order to maintain a proper working temperature of the oil and water in the tanks under adverse conditions, steam coils 17 are led 45 around the two tanks and are inclosed within suitable casings 18 which insure that the heat radiated from the coils will properly warm the contents of the tanks. These coils are both supplied with steam from the boiler 50 through pipes 19.

Directly mounted upon the forward end of the car is a sheet metal housing 20. This housing is permanently attached to the front of the car and extends outwardly over the 55 track. The forward end of the housing is

opened and thus presents a large radiating area through which heat may pass from oil burners 21, which are inclosed within the housing. These burners are positioned with their nozzles extending horizontally so that 60 their flames may impinge against the snow bank and act to rapidly melt the same. As shown in the drawing, the burners are arranged in two sets, one above the other. It is evident that various other changes could 65 be made in the arrangement of the burners without departing from the spirit of the invention and it is to be understood that a series of the burners extend horizontally across and within the housing. Due to the 70 connection 22, the burners may be swung vertically, when desired, to direct the flames against certain parts of the snow bank. In order to increase or decrease the intensity of the heat emanated from the mouth of 75 the housing 20, a sliding joint 23 has been provided to allow the burners to be moved horizontally in relation to the oil feed pipe 24. The upper portion of the housing is fitted with a hinged roof 25 pivoted upon 80 the rod 26. This member may be swung upwardly to increase the area of the opening through which the heat is emanated and will thus allow the heat to be applied to snow banks of considerable height. In order to 85 disintegrate the snow, as presented to the mouth of the housing, breaker arms 27 are mounted upon vertical shafts 28. These shafts are carried by the housing and stand vertically and in spaced relation to each 90 other across the mouth thereof. These arms travel in horizontal planes and will drag through the face of the snow drift to loosen the snow as melted. Power is derived for the shafts 28 through suitable gearing 95 connected with a countershaft 29, and which in turn is driven by a chain shaft 30. Shaft 30 is fitted with a sprocket 31 carrying a sprocket chain 32 which leads to a sprocket 33 mounted upon the forward axle 34 of the car 100 truck 11. It will thus be seen that as the car advances, the shafts 28 will be placed in motion and will continue in motion throughout the advancing movement of the car. Although it may not be proven to be necessary, 105 the fuel supply 24 is provided with a pump 35 which is driven by a small steam engine 36, deriving its power from the boiler. This pump will produce a force feed for the fuel and will insure that proper atomization of 110

fuel will be effected in the nozzles. In operation, heat is generated in the fire-box of the boiler and this in turn used to warm the oil and water tanks 14 and 16 by means of their coils 17. The car may then be drawn or pushed along the track to be cleaned and when the point of operation is reached, the burners 21 may be lighted. The flame from these burners will extend outwardly through the open mouth of the housing 20 and strike the snow, at the same time raising the temperature of the air within the housing to a high degree. It may be desired to line the housing with asbestos in order to insure that the major part of the heat generated by the burners will be thrown outwardly against the snow bank. As the cars move forwardly, the arms 27 will be actuated to claw the snow and to disintegrate it as it is heated. In the event that the bank is high, the roof 25 may be swung upwardly and held in its position by tightening lock-nuts 37 carried by bolts on the sides of the roof, which bolts extend through arcuate slots 38 in the sides of the housing.

The steam from the boiler will be conducted from a pipe 19 to the pipe 24 or otherwise placed in communication with the burners 21 so that this steam will act upon the oil to cause it to more thoroughly vaporize as it passes from the burner, thus producing a more volatile fuel. It will also be recognized that by this arrangement, the steam which is sprayed out through the nozzles will act to assist in melting the snow.

It will thus be seen that the invention here disclosed, provides an effective portable device which will readily act to clear snow and ice from a track or roadway, irrespective of the weather conditions during the time of operation and without danger of the apparatus being rendered inoperative, due to the extremely low temperatures.

While I have shown the preferred form of my invention, it will be understood that various changes in the combination, construction and arrangement of parts may be made by those skilled in the art, without departing from the spirit of the invention as claimed.

Having thus described my invention, what I claim and desire to secure by Letters Patent is:—

1. A snow melting apparatus including a boiler oil and water tanks and heating means connected with the boiler, a movable

support upon which they are mounted, a fixed divergent hood supported from the movable vehicle, a supplemental hood hinged to the fixed hood with means to open and vary the divergency, a pump upon the vehicle, jet pipes leading therefrom and discharging hot gases from the hood front, said pipes being telescoped and adjustable, a vertical shaft journaled at the front of the hood with radially projecting arms and means driven from the vehicle to rotate the shaft and arms.

2. In an apparatus of the character described, oil and water containers with inclosing heating coils; a boiler with which said coils are connected, and a movable vehicle upon which they are carried, a hood fixed to the front of the vehicle and diverging forwardly a series of burners and a conducting pipe, a pump by which oil vapor and heated gases are forced through the pipe to the burner, an adjustable hood hinged to the main hood, and a series of horizontally projecting arms and means to rotate them horizontally to loosen and disburse the snow outwardly.

3. In a device of the character described, a fuel supply tank, a vehicle upon which said tank is mounted having a housing open at the front, a plurality of burners extending into the housing, means to discharge vapor from said tank to the burners, a hood hinged to the housing having an open mouth to allow flames from the burners to be projected therethrough, and means whereby the opening through which the flames are projected may be variably adjusted.

4. In a device of the character described, a fuel supply tank, a vehicle upon which said tank is mounted having a housing open at the front, a plurality of burners extending into the housing, means to discharge vapor from said tank to the burner, a hood hinged to the housing having an open mouth to allow flames from the burners to be projected therethrough, means to adjust the burners forward and backward or to tilt them vertically, and means to adjust the hood relative to the discharge from the burners.

In testimony whereof I have hereunto set my hand in the presence of two subscribing witnesses.

JAMES BARRY.
